UNITED STATES PATENT OFFICE.

DONALD K. CAMPBELL, OF CHICAGO, ILLINOIS, ASSIGNEE OF ONE-FOURTH TO OSCAR V. PALMQUIST AND ONE-FOURTH TO OSCAR W. JOHNSON, BOTH OF CHICAGO, ILLINOIS.

VENDING-MACHINE.

1,263,033.

Specification of Letters Patent. Patented Apr. 16, 1918.

Application filed May 17, 1917. Serial No. 169,232.

To all whom it may concern:

Be it known that I, DONALD K. CAMPBELL, a citizen of the United States, residing at Chicago, in the county of Cook and State 5 of Illinois, have invented a new and useful Improvement in Vending-Machines, of which the following is a specification.

My invention relates more particularly to vending machines for vending news- 10 papers and other similar articles, preferably under the control of coin-controlled mechanism; and my object is to provide improvements in machines of this kind which shall render the machine simple and eco- 15 nomical of construction, require minimum economy in operating the same on a commercial basis, and be positive in operation, and generally to so improve upon machines of this kind as hitherto provided that they 20 shall be better adapted to perform the functions for which they are provided.

Referring to the accompanying drawings:

Figure 1 is a view in front elevation of a 25 machine constructed in accordance with my invention, certain portions thereof being broken away to disclose interior details, the parts of the machine being shown in normal position.

Fig. 2 is a fragmentary view in rear elevation of certain parts of the mechanism which operate to effect the discharge of the papers, one at a time, from the machine.

Fig. 3 is a broken view like Fig. 1, showing the discharge mechanism in one position it assumes during the operation thereof to discharge a paper.

Fig. 4 is a view like Fig. 3 showing parts of this mechanism in the position they assume intermediate the position shown in Fig. 3 and the normal position to which they return (Fig. 1).

Fig. 5 is a broken section taken at the line 5 on Fig. 4 and viewed in the direction of the arrow.

Fig. 6 is a section taken at the line 6 on Fig. 1 and viewed in the direction of the arrow, the parts of the apparatus being shown in the positions shown in Fig. 1.

Fig. 7 is a view like Fig. 6 with the upper part of the machine broken away and show-

ing the positions assumed by the parts shown in Fig. 3.

Fig. 8 is a section taken at the line 8 on Fig. 3 and viewed in the direction of the arrow; and

Fig. 9, a section taken at the line 9 on Fig. 1 and viewed in the direction of the arrow.

In accordance with the preferred embodiment of my invention, I provide a casing 10 shown as formed of metal, but which may be of any other suitable material, this casing being of general rectangular form, and preferably of such dimensions that the papers to be vended and represented at 11 may be readily inserted therein, and it may be here stated that it is preferred that the casing be of such proportions that it will accommodate papers when folded once, or, in other words, in the condition in which they are generally delivered from the newspaper offices, and are exhibited in newspaper stands. The front wall of the casing, represented at 12, preferably has a forwardly and downwardly-inclined section 13 containing a slot 14 of a length slightly greater than the width of the newspapers to be vended, and below this section 13 are trough-shaped members 15 adjustably supported on the bottom 16 of the casing 10, as and for the purpose hereinafter described, these troughs affording upwardly-projecting flanges 17 at their forward edges and upwardly-projecting flanges 18 at their rear edges, the flanges 18 serving as stop surfaces against which the papers 11 in flatwise abutting condition as shown in Fig. 6 are spring-pressed, as through the medium of a follower-board 19 which extends lengthwise of the casing 10 and is of substantially the width of the papers 11, this board being spring-pressed forwardly through the medium of a spring device 20 formed of a spring-coil section 21 secured to the bottom 16 of the casing 10 and having two arms, directed toward opposite ends of the casing, one only of these arms being shown and represented at 21', which press against the follower-board 19 at their lower ends and against the papers at their upper portions 22, thus exerting a pressure against the papers tending to force them forward at

all times. The top of the casing 10, represented at 23, is preferably hinged thereto, as represented at 24, and by preference is connected with mechanism whereby, upon lifting the top 23, the follower-board 19 is automatically shifted to the rear of the casing to facilitate and expedite the filling of the casing 10 with the papers to be vended. To this end each of the spring-arms 21 has connected therewith a cable 24, one only of which is shown, which extends around pulleys 25, 26 and 27 secured to the rear and front walls of the casing and connected at their ends 28 with a lug 29 on the cover. The arrangement is such, as will be manifest from the drawing, that when the lid 23 is raised the follower 19 will be automatically moved to the rear of the casing. A description of the mechanism by which the papers are moved to discharge position, one at a time, is as follows:

The casing 10 is provided with a depending housing 30 in which the mechanism just referred to is located. This housing 25 contains a stationary shaft 31, shown as a bolt, which is secured in the front and rear walls 32 and 33 of the housing. Rotatably supported on the shaft 31 are two blades 34 and 35, each of which is formed of a section 36 and a section 37. The blades 34 and 35 are rotatably supported on the shaft 31 at the sections 36, this section of the blade 35 being deflected forwardly slightly, as indicated at 38, to compensate for the thickness of the metal of which these parts are formed, to cause the outer edges of the sections 36 to extend in the same vertical plane. The sections 37 are connected with the coöperating sections 36 through the medium of spring hinges 39 which are so constructed and arranged that they tend normally to force the sections 37 rearwardly. The section 36 of the blade 35 is provided with an extension 40 at the opposite side of 40 the shaft 31 which terminates in a blade-section 41 and an intermediate forwardly offset portion 42 presenting a substantially arc-shaped shoulder 43, the front face of the blade-section 41 inclining rearwardly as 45 represented at 44 toward the upper extremity of the blade-section 41, viewing the latter in the position shown in Fig. 2. The section 37 of the blade 34 bears against the blade-section 41 in the rear thereof, under 50 the action of its spring hinge and the section 37 of the blade 35 is held to a limited rearward movement by stop lugs 35^a on the section 36 of this blade engaging this section 37.

60 The outer extremities of the sections 37 are curved rearwardly as represented at 45, to provide the relatively pointed extremities 46 which lie in the same vertical plane, and preferably in substantially the same

vertical plane as the upper extremity of 65 the blade-section 41, the portion 46 of the blade 34 moving closely adjacent to the forward face of the blade-section 41, and thus in the rear of the forward edge of the shoulder 43 and the portion 44.

70 The members 34 and 35 are pivotally connected at their sections 36 with links 47, which are pivotally connected at their lower end with a pin 49 connected with a finger-piece 50 that slides up and down in a slot 51 in the wall 52 of the housing 30, the rear end of this pin 49 being connected with the lower end of a coil-spring 52, the upper end of which is connected with the shaft 31, this spring serving to return the 80 mechanism above described to the normal position represented in Fig. 1 after actuation thereof to discharge a newspaper as hereinafter described.

85 The parts of the device in the normal position assume the positions shown in Fig. 1, in which position the blades 34 and 35 extend at their sections 37 across the forwardmost one of the papers 11 and serve to prevent the unauthorized withdrawal of a 90 paper from the machine. In this position of the parts the member 40 is withdrawn to the position shown in Fig. 1, namely, that wherein it extends below the plane in which the lowermost edges of the papers extend. Upon lowering the member 50 against the action of the spring 52, the blades 34 and 35 are caused to swing upon the shaft 31 downwardly and away from each other, and the member 40 is caused to swing upwardly, the positions assumed by these parts in the extreme lower position of the member 50 being that shown in Fig. 3. In this operation the uppermost portion of the blade-section 41 enters between the forwardmost 100 one of the papers and the next one behind it, as illustrated in Figs. 3 and 7, and the curved portion 43 engages the lower edge of the paper, forcing the latter upwardly above the upper edges of the flanges 18 and 110 slightly forwardly by reason of the offset portion 44, as shown in Fig. 7. Upon the operator releasing his pressure on the part 50, the spring 52 returns these parts of the delivery mechanism to the position shown 115 in Fig. 1, and in moving to this position the points 46 of the sections 37 enter behind the forwardmost one of the papers practically while at its greatest height, and cam this paper forwardly to a position in which 120 it extends forward of the flanges 18 and may be readily withdrawn therefrom by the operator, the members 34 and 35 in this movement to normal position thus moving across the face of the paper next to be delivered and thereby preventing its unauthorized removal.

125 It will be understood from the foregoing

that the action of the mechanism generally stated is the projection upwardly of the blade-section 41 between the first two papers, the lifting of the first or forward paper upwardly and, preferably, its slight projection forward, beyond the upper edges of the flanges 18, and the movement of the blades 34 and 35 to a position in which they extend across the front of the second paper and in so moving preferably force the first paper farther in a forward direction.

The trough members 15 are preferably made adjustable to permit them to be moved forwardly from the position shown in Fig. 6 for accommodating the machine to papers of greater thickness. To this end the members 15 are provided with depending lugs 53 which are guidedly confined in slots 54 in the bottom plate 16, these troughs also carrying depending lugs 55 moving in slots 56 and to which screws 57, having threaded engagement at their slot-equipped ends 58 with openings 59 in the wall 32, are pivotally connected, whereby, upon adjusting these screws, the members 15 may be moved forward or backward, as desired.

The sections 37 are hinged to the sections 36 to permit these sections to yield forwardly in moving across the forward face of a paper, and are of special importance in the case of the adjustment of the trough members 15 to a position forward of that shown in Fig. 6, the sections 37 yielding forwardly in bearing against the front surface of the paper which directly engages the flanges 18, but immediately springing back to position in which their points lie substantially in the same vertical plane as the upper extremity of the blade-section 41, upon the relative movement of these points 46 to the forwardmost paper, out of engagement with each other.

The delivery mechanism above described is shown in the drawings as associated with coin-controlled mechanism whereby the delivery mechanism cannot be operated to deliver a paper until the proper coin has been deposited in the machine, a description of this coin-controlled mechanism being as follows:

Located to one side of the shaft 31, and adjacent the outer periphery of the member 35, is a stop lever 60 pivoted, as indicated at 61, to the housing and so constructed and arranged that it normally extends at its upper end 62, by reason of its weighted lower end, into the path of movement of a shoulder 63 on the member 35 in moving from normal position (Fig. 1) to delivery position, and thus normally prevents the movement of the blades 34 and 35 to a position in which delivery may be effected. Located alongside of the lever 60 is a coin-chute 64 open at its upper end, at which it

communicates with a slot in the front wall 65 of the housing. The side walls 65 and 66 of the coin-chute extend short of the lower ends of the other opposed walls 67 and 68, the lower end of the lever 60 in the normal position of the parts projecting into this chute as represented in Fig. 1. The right-hand edges of the walls 67 and 68 in Fig. 4 are beveled, as indicated at 69, and located adjacent thereto is a spring-plate 70 secured to the wall 66 as at 71, this spring-member in combination with the lever 60 and the walls 67 and 68 forming a constricted portion into which the coin, such as that represented at 72, drops upon being deposited into the chute 64, the weight of the coin 80 swinging the lever 60 to a position in which its upper end 62 is moved out of the path of the shoulder 63. The opening, however, provided between these several parts, when the lever 60 swings to the unlocking position 85 stated, is not sufficiently large to permit the coin to discharge from the chute, the discharge of the coin therefrom being effected by means of a spring-member 73 supported on the pin 74 secured to the housing and at 90 its opposite end to the lower end of the spring-member 70, as indicated at 75, and extending at an inclinedly-disposed section 76 into the path of movement of the pin 49 in moving from the position illustrated in Fig. 1 to the position shown in Fig. 3, which causes the member 70 to be sprung to the position shown in Fig. 3 in which the coin 72 is released from the chute and drops into the housing, the spring-member 70 returning to normal position (Fig. 1) upon the movement of the delivery apparatus to the normal position shown in Fig. 1.

While I have illustrated and described a particular construction in which my invention is embodied, I do not wish to be understood as limiting it thereto, as the same may be variously modified and altered without departing from the spirit of my invention, it being my intention to claim my invention as fully and completely as the prior state of the art will permit.

What I claim as new and desire to secure by Letters Patent is—

1. In a vending machine, the combination of a casing for storing on edge the articles to be vended and provided with an outlet, a member supported to be moved into a position between the forwardmost one of said articles and the article next thereto, a member supported to be moved into engagement with the front surface of the last-referred-to article, and means for actuating said members in opposite directions to cause said first-referred-to member to be moved into said position and said other member to be out of engagement with the articles for separating the forwardmost one thereof.

from the others and thereafter moving said first-referred-to member to a position below said articles and the other of said members across the front of the article next to be delivered.

2. In a vending machine, the combination of a casing for storing on edge the articles to be vended and provided with an outlet, a rotatably-supported member adapted to be moved into a position between the forwardmost one of said articles and the article next thereto, a rotatably-supported member adapted to be moved into engagement with the front surface of the last-referred-to article, and means for actuating said members to cause said first-referred-to member to be moved into said position and said other member to be out of engagement with the articles for separating the forwardmost one thereof from the others and thereafter moving said first-referred-to member to a position below said articles and the other of said members across the front of the article next to be delivered.

25 3. In a vending machine, the combination of a casing for storing on edge the articles to be vended and provided with an outlet, a cam member supported to be moved into a position between the forwardmost one of said articles and the article next thereto and cam said forwardmost article forward, a member supported to be moved into engagement with the front surface of the article next to said forwardmost article, and means for actuating said members in opposite directions to cause said first-referred-to member to be moved into said position and said other member to be out of engagement with the articles for separating the forwardmost one thereof from the others and thereafter moving said first-referred-to member to a position below said articles and the other of said members across the front of the article next to be delivered.

45 4. In a vending machine, the combination of a casing for storing on edge the articles to be vended and provided with an outlet, an abutment for the articles located adjacent said outlet, means for forcing said articles toward said abutment, and a plurality of means operating to alternately lift the forwardmost one of said articles above said abutment, shift it forwardly and separate it from the others for delivery through said outlet said 50 operating means forming a barrier to the withdrawal of the others of said articles from said casing through said outlet.

5. In a vending machine, the combination of a casing for storing on edge the articles to be vended and provided with an outlet, an abutment for the articles located adjacent said outlet, means for forcing said articles toward said abutment, a member supported to be moved into a position be-

tween the forwardmost one of said articles 65 and the articles next thereto, and adapted to raise the forwardmost one of said articles above said abutment and separate it from the others for delivery through said outlet, a member supported to be moved into engagement with the front surface of the article immediately in the rear of the forwardmost one thereof, and means for actuating said members to cause said first-referred-to member to be moved into said position and said other member to be out of engagement with the articles to effect the separation of the forwardmost one thereof from the others and thereafter moving said last-referred-to member to a position below 80 said articles and the other of said members across the front of the article next to be delivered.

6. In a vending machine, the combination of a casing for storing on edge articles to be vended and provided with an outlet, an abutment for the articles located adjacent said outlet, means for forcing said articles toward said abutment, a rotatably-supported member adapted to be moved into a position between the forwardmost one of said articles and the article next thereto and lift the forwardmost one of said articles above said abutment and separate it from the others for delivery through said outlet, a rotatably-supported member adapted to be moved into engagement with the front surface of the article immediately in the rear of the forwardmost one thereof, and means for actuating said members to cause said first-referred-to member to be moved into said position and said other member to be out of engagement with the articles to effect the separation of the forwardmost one thereof from the others and thereafter moving said last-referred-to member to a position below 95 said articles and the other of said members across the front of the article next to be delivered.

7. In a vending machine, the combination of a casing for storing on edge articles to be vended and provided with an outlet, an abutment for the articles located adjacent said outlet, means for forcing said articles toward said abutment, a member supported to be moved into a position between the forwardmost one of said articles and the article next thereto, and adapted to raise the forwardmost one of said articles above said abutment and separate it from the others for 100 delivery through said outlet, a member supported to be moved into engagement with the front surface of the article immediately in the rear of the forwardmost one thereof, said last-named member being formed of relatively yieldable portions whereby this member may yield in a forward direction, and means for actuating said members to cause 105

- 5 said first-referred-to member to be moved into said position and said other member to be out of engagement with the articles to effect the separation of the forwardmost one thereof from the others and thereafter moving said last-referred-to member to a position below said articles and the other of said members across the front of the article next to be delivered.
- 10 8. In a vending machine, the combination of a casing for storing on edge the articles to be vended and provided with an outlet, an abutment for the articles located adjacent said outlet, means for forcing said articles toward said abutment, a rotatably-supported member adapted to be moved into a position between the forwardmost one of said articles and the article next thereto and adapted to raise the forwardmost one of said articles above said abutment and separate it from the others for delivery through said outlet, a rotatably supported member adapted to be moved into engagement with the front surface of the article immediately in the rear of the forwardmost one thereof, said last-named member being formed of relatively yieldable portions whereby this member may yield in a forward direction, and means for actuating said members to cause said first-referred-to member to be moved into said position and said other member to be out of engagement with the articles to effect the separation of the forwardmost one thereof from the others and thereafter moving said last-referred-to member to a position below said articles and the other of said members across the front of the article next to be delivered.
- 15 9. In a vending machine, the combination of a casing for storing on edge the articles to be vended and provided with an outlet, a member supported to be moved into a position between the forwardmost one of said articles and the article next thereto, a pair of members supported to be moved into engagement with the front surface of the last-referred-to article, and means for actuating said members to cause said first-referred-to member to be moved into said position and said other members to be out of engagement with the articles for separating the forwardmost one thereof from the others and thereafter moving said first-referred-to member to a position below said articles and the other of said members across the front of the article next to be delivered.
- 20 10. In a vending machine, the combination of a casing for storing on edge the articles to be vended and provided with an outlet, an abutment for the articles located adjacent said outlet, means for forcing said articles toward said abutment, a member supported to be moved into a position between the forwardmost one of said articles and the article next thereto, and adapted to raise the forwardmost one of said articles above said abutment and force it over said abutment, a member supported to be moved into engagement with the front surface of the article immediately in the rear of the forwardmost one thereof, and means for actuating said members to cause said first-referred-to member to be moved into said position and said other member to be out of engagement with the articles to effect the separation of the forwardmost one thereof from the others and thereafter moving said last-referred-to member to a position below said articles and the other of said members across the front of the article next to be delivered.
- 25 11. In a vending machine, the combination of a casing for storing on edge articles to be vended and provided with an outlet, an abutment for the articles located adjacent said outlet, means for forcing said articles toward said abutment, a member supported to be moved into a position between the forwardmost one of said articles and the article next thereto, and adapted to raise the forwardmost one of said articles above said abutment and force it over said abutment, a member supported to be moved into engagement with the front surface of the article immediately in the rear of the forwardmost one thereof, and means for actuating said members to cause said first-referred-to member to be moved into said position and said other member to be out of engagement with the articles to effect the separation of the forwardmost one thereof from the others and thereafter moving said last-referred-to member to a position below said articles and the other of said members across the front of the article next to be delivered.
- 30 12. In a vending machine, the combination of a casing for storing on edge the articles to be vended and provided with an outlet, a member supported to be moved into a position between the forwardmost one of said articles and the article next thereto and force the forwardmost one of said articles forwardly, a member supported to be moved into engagement with the front surface of the one of the articles immediately in the rear of said forwardmost article, and means for actuating said members in opposite direction to cause said first-referred-to member to be moved into said position and said other member to be out of engagement with the articles for separating the forwardmost one thereof from the others and thereafter moving said first-referred-to member to a position below said articles and the other of said members across the front of the article next to be delivered.
- 35 13. In a vending machine, the combination of a casing for storing on edge the articles to be vended and provided with an outlet, an abutment for the articles located adjacent said outlet and adapted to be adjusted into varying positions, means for

- forcing said articles toward said abutment, and means operating to lift the articles one at a time above said abutment and effect the delivery of the articles from the casing.
- 5 14. In a vending machine, the combination of a casing for storing on edge the articles to be vended and provided with an outlet, an abutment for the articles located adjacent said outlet and adapted to be adjusted into varying positions, means for forcing said articles toward said abutment, and a plurality of means operating to alternately lift the forwardmost one of said articles above said abutment and separate it 10 from the others for delivery through said outlet said operating means forming a barrier to the withdrawal of the others of said articles from said casing through said outlet.
- 20 15. In a vending machine, the combination of a casing for storing on edge the articles to be vended and provided with an outlet, an abutment for the articles located adjacent said outlet and adjustable into different positions, means for forcing said articles toward said abutment, a member adapted to be moved into a position between the forwardmost one of said articles and the article next thereto and lift the forwardmost article above said abutment, a member adapted to be moved into engagement with the front surface of the article immediately in the rear of the forwardmost one thereof, said last-referred-to member being 30 formed of relatively flexible portions adapted to yield in a forward direction, and means for actuating said members to cause said first-referred-to member to be moved into said position and said other member to be out of engagement with the articles for separating the forwardmost one thereof from the others and thereafter moving said first-referred-to member to a position below said articles and the other of said members 40 across the front of the article next to be delivered.
- 45 16. In a vending machine, the combination of a casing for storing on edge the articles to be vended and provided with an outlet, a member supported to be moved into a position between the forwardmost one of said articles and the article next thereto, a member supported to be moved into engagement with the front surface of the last-referred-to article, said members being movable in substantially parallel planes, and means for actuating said members in opposite directions to cause said first-referred-to member to be moved into said 50 position and said other member to be out of engagement with the articles for separating the forwardmost one thereof from the others and thereafter moving said first-referred-to member to a position below said
- articles and the other of said members across the front of the article next to be delivered.
17. In a vending machine, the combination of a casing for storing on edge articles to be vended and provided with an outlet, a member supported to be moved into a position between the forwardmost one of said articles and the article next thereto, said member being provided with a camming surface for camming the forwardmost article forwardly and having a stop surface 70 adapted to engage the lower edge of the article and lift the latter, a second member supported to be moved into engagement with the front surface of the article immediately in the rear of the forwardmost one thereof following the said camming and lifting operation, and means for actuating said members to cause said first-referred-to member to be moved into said position and said other member to be out of engagement with the articles to effect the separation of the forwardmost one thereof from the others and thereafter moving said last-referred-to member to a position below said articles and the other of said members across the front 80 of the article next to be delivered.
18. In a vending machine, the combination of a casing provided with a removable closure, members in the casing between which the articles to be vended extend, one 90 of said members being in the form of a follower supported in said casing independently of said closure in all positions of the latter and movable therein toward and away from the other of said members, means tending to move the follower toward said other member, and means operated by said removable closure constructed and arranged to retract the follower upon the act of opening the closure and permit the follower to 100 move toward said other member upon the movement of said closure to closed position.
19. In a vending machine, the combination of a casing for storing on edge the articles to be vended and provided with an 110 outlet, a member supported to be moved into a position between the forwardmost one of said articles and the article next thereto, a member supported to be moved in a plane substantially parallel with that in which said first-referred-to member moves, and into engagement with the front surface of the last-referred-to article, and means for actuating said members in opposite directions to cause said first-referred-to member 120 to be moved into said position and said other member to be out of engagement with the articles for separating the forwardmost one thereof from the others and thereafter moving said first-referred-to member to a position below said articles and the other of said members across the front of the article next to be delivered.

20. In a vending machine, the combination of a casing provided with a removable closure, members in the casing between which the articles to be vended extend, one of said members being in the form of a follower supported in the casing independently of said closure in all positions of the latter, to move in a substantially horizontal plane toward and away from the other of said members, means tending to move the follower toward said other member, and means operated by said removable closure constructed and arranged to retract the follower upon the act of opening the closure and permit the follower to move toward said other member upon the movement of said closure to closed position.

DONALD K. CAMPBELL.
